UNITED STATES PATENT OFFICE.

JENNIE LYNN EDWARDS, OF VALLEY, WASHINGTON.

CORSET-RETAINER AND HOSE-SUPPORTER.

1,276,504.

Specification of Letters Patent. Patented Aug. 20, 1918.

Application filed May 3, 1918. Serial No. 232,363.

To all whom it may concern:

Be it known that I, JENNIE LYNN EDWARDS, a citizen of the United States, residing at Valley, in the county of Stevens and 5 State of Washington, have invented certain new and useful Improvements in Corset-Retainers and Hose-Supporters; and I do hereby declare the following to be a full, 10 clear, and exact description of the invention, such as will enable others skilled in the art to which it appertains to make and use the same.

This invention relates to means for holding down or retaining in position, ladies' 15 corsets and its primary object is to provide a corset retainer of simple and economical construction especially intended to hold down the corset while the corset wearer is using half hose instead of the usual long 20 hose reaching above the knee.

A further object is to provide a corset retainer to be worn a few inches above the 25 knee and loose enough to be perfectly comfortable while fitting the general conformation of the leg at this point in such a manner as to prevent it slipping up.

A further object is to provide a corset retainer of the class before specified with means for attachment through the rings of 30 the hose supporters with which corsets are usually provided when manufactured.

Still further objects will be revealed as the description proceeds.

With these objects in view the invention 35 consists in the improved construction, arrangement and combination of the parts of a device of the character specified, which will be hereinafter fully described and afterward specifically claimed.

40 In order that the construction and operation thereof may be readily comprehended, I have illustrated an approved embodiment of my invention in the accompanying drawings, and will now proceed to fully describe 45 the same in connection with said drawings, in which—

Figure 1 represents a female figure provided with a corset, my improved corset retainer, and half hose, to illustrate the relationship of the several devices, and

50 Fig. 2, about one-half of a corset retainer constructed in accordance with my invention, on an enlarged scale, this half and the omitted half, being substantial duplicates so 55 that the invention may be fully understood by specifically describing one half in connec-

tion with the description of the relation of the parts as shown in Fig. 1.

Like reference characters mark the same parts in both of the figures of the drawing.

Referring specifically to the drawing, 5 indicates an ordinary corset on a human figure, and 6 an ordinary pair of half hose held up, as ordinarily, by a piece of elastic inserted in the hem 7.

65 The corset 5 is supplied with clasps 8 to which my improved corset retainer is connected, as hereinafter described.

70 My corset retainer comprises two triangular pads 9 and 10, each consisting of two sections which are indicated in the enlarged view of pad 9 in Fig. 2 as 9^a and 9^b, said sections being connected at their upper ends by a ring 11 secured by means of a loop 12 of tape sewed to the two sections.

75 Each pad has a spring for elastically holding its sections together, said spring comprising a double coil 13 at the top secured to the pad, with an arm, as at 14 and 15, lying upon each section, parallel with the 80 meeting edges of the sections, which arms are turned upward and outward at their lower ends forming arms 16 and 17 which are engaged in tape loops 18, 19 and secured to the sections by sewing the loops 85 thereto.

The tape loop 18 is short, terminating on the section 9^a and carrying at its outer end a metal loop 20 having thereon a hook 21 which is engaged by a metal loop 22 on the 90 body tape 23 which is extensible in a well known manner by manipulating a loop 24 to which the end of the body tape is secured.

The arm 17, in the tape loop 19 is, as before stated, secured to the section 9^a by sewing the loop 19 to the section, and the tape loop is extended in the form of a single tape 25 to take in the pad 10, connected also to tape 26 beyond the slideable metal loop 24, said pad being constructed, in all respects, 100 similarly to the pad 9 heretofore described.

To place the corset retainer in position, the metal rings on the pads are simply engaged on the clasps 8 provided on the corset as hose supporters, when the length of 105 the surrounding tape may be adjusted in the manner described, the binding of the retainer on the leg of the wearer being elastic owing to the action of the springs to normally hold the two sections together.

110 The retainer, as described, will elastically hold the corset down without any connection

2
to a hose supporter, and the wearer is therefore permitted to wear half hose which permit much more freedom of movement than would the long hose reaching above the knee.

The utility and simplicity of my invention will be evident from the foregoing and I desire to be understood that changes and variations may be made from the specific 10 construction described, without departing from the spirit and scope of the invention.

Having thus fully described my invention, what I claim as new and desire to secure by Letters Patent of the United States is:

15 1. A corset retainer comprising a triangular pad, in two sections, a ring connecting the sections at the top, a spring to normally tend to draw the sections together, and a tape connected to the pad and adapted to encircle the leg of the wearer.

20 2. A corset retainer comprising a triangular pad, in two sections, a ring connecting the sections at the top, a spring to normally tend to draw the sections together, and a 25 tape connected to the pad and adapted to encircle the leg of the wearer, one end of the circle the leg of the wearer, one end of the body tape carrying a hook and the other end a metal loop to engage said hook.

3. A corset retainer comprising a triangular pad, in two sections, a ring connecting the sections at the top, a spring to normally tend to draw the sections together, and a tape connected to the pad and adapted to encircle the leg of the wearer, said spring comprising a coil, and legs extending from said coil on opposite sides and connected respectively to the two sections of the pad.

4. A corset retainer comprising a triangular pad, in two sections, a ring connecting the sections at the top, a spring to normally tend to draw the sections together, and a tape connected to the pad and adapted to encircle the leg of the wearer, said spring comprising a coil connected to the pad at the top, a leg depending from each side of the coil along each of the sections and turned upward and outward at its lower ends and secured to the section.

In testimony whereof I have signed my name to this specification in the presence 50 of two subscribing witnesses.

JENNIE LYNN EDWARDS.
